UNITED STATES PATENT OFFICE.

HOWARD D. COLMAN AND BURT A. PETERSON, OF ROCKFORD, ILLINOIS, ASSIGNEES
TO HOWARD D. COLMAN, LUTHER L. MILLER, AND HARRY A. SEVERSON, COPART-
NERS DOING BUSINESS AT ROCKFORD, ILLINOIS, AS BARBER-COLMAN COMPANY.

BOBBIN-CLUSTER.

1,115,509.

Specification of Letters Patent.

Patented Nov. 3, 1914.

Application filed February 21, 1910. Serial No. 545,142.

To all whom it may concern:

Be it known that we, HOWARD D. COLMAN and BURT A. PETERSON, citizens of the United States, residing at Rockford, in the 5 county of Winnebago and State of Illinois, have invented certain new and useful Improvements in Bobbin-Clusters, of which the following is a specification.

This invention relates to a support for a 10 plurality of bobbins and the like, which is adapted for use in machines for unwinding yarn from one container and winding it upon another container.

In machines of this class which are intended to handle a large number of threads, as in warpers or beaming machines, it is essential to practical success that the bobbins or other containers being emptied be grouped as compactly as possible, having regard to accessibility, convenience in replacing bobbins, and non-interference of the strands with one another.

When a thread is being rapidly unwound from a bobbin, the running thread "balloons" or forms itself into a loop surrounding the bobbin. Such ballooning, when excessive, causes injury to the thread, reduces the practical speed of winding by placing a drag on the thread, and causes interference 30 with adjacent threads.

The object of this invention is to attain the greatest possible compactness in bobbin-supports of this class and to prevent excessive ballooning of the yarn.

In the accompanying drawings, Figure 1 is an elevation of a bobbin cluster embodying the features of our invention. Fig. 2 is a top plan view, showing said cluster. Fig. 3 is a sectional view taken in the plane of line 40 3 3 of Fig. 1. Fig. 4 is an under side view of the cluster. Fig. 5 is a section on line 5 5 of Fig. 3.

The cluster is herein shown as mounted upon a support comprising two angle irons 45 1 and a plate 2 attached to said angle irons. In Fig. 2 an entire plate and portions of two others have been illustrated to indicate how closely clusters embodying our invention may be grouped. For convenience in replacing bobbins, the cluster is rotatably connected with its support, the rotatable connection being obtained in this instance as follows: The lower end of the base 3 of the cluster 50 has an annular rabbet therein forming a

shoulder 4 to rest upon the edges of a round opening 5 in the plate 2. The base 3 is removably secured to the plate 2 by suitable means such as a plurality of screws 3^a seated in the base and having heads arranged to underlie the edges of the opening 5. These 60 heads are cut away at one side, as indicated in Fig. 4, so that the heads, when turned into the position shown in said figure, shall offer no obstruction to the removal of the base 3 from the support 2.

The cluster comprises four bobbin spindles 6 having a hinge connection with the base 3. In this instance the hinge connection is formed as follows: A transverse pivot 7 is fixed to the spindle, with its ends lying 70 in recesses 8 in a pair of lugs 9 on the base 3. Above the lugs 9 is a stop portion 10 on the base, against which stop portion the spindle is normally held by a coiled spring 11. Each spring 11 is attached at its ends to two diametrically opposite spindles. The portion 7^a of the spindle extending below the pivot 7 constitutes a stop to limit the outward pivotal movement of the upper part, or spindle proper, said stop 6^a impinging upon the adjacent part of the base 3. Upon each spindle is an enlargement 12 forming a seat for the bobbin. The running thread is arranged to pass through a suitable guide located near the upper ends of the cluster of 85 bobbins and common to all of them.

In bobbin clusters heretofore produced, the bobbins have been inclined, the axes of the bobbins extending through the common thread guide in order that the 90 threads might unwind from the bobbins and pass to the guide without catching on the upper ends of the bobbins. This arrangement has necessarily caused the lower ends of the bobbins to be spread apart, and 95 the supporting base to be of corresponding dimensions. We have succeeded in making the bobbin cluster more compact by disposing the spindles in parallel relation and providing supplemental thread guides between 100 the bobbins and the common guide.

The common guide is indicated at 13 in Figs. 1 and 2. While it may be of various forms, we have herein shown a guide made of wire and comprising an open coil and an 105 attaching stem, said stem being secured to a suitable support 14.

The supplemental or intermediate guides

consist preferably of a plate 15 located centrally of the bobbins and between them and the guide 13. Said plate has four straight guide edges 16 across which the thread runs in passing from the bobbins to the eye 13. Each guide edge 16 lies in a vertical plane extending through the axis of a spindle, said plane being at right angles to a vertical plane passing through the spindle and the guide 13. This arrangement of the guide edge permits of the freest possible movement of the thread from all points on the bobbin. Connecting the guide edges 16 are curved edges 17 across which the running thread passes in moving from an exhausted bobbin to a full bobbin.

To prevent excessive ballooning and contact of the "balloon" with adjacent bobbins, partitions 18 are placed between the bobbins. These partitions may, if desired, be formed of two plates, each having a longitudinal central slot 19 extending from one end of the plate to a point about midway of the plate, whereby the two plates may be disposed in intersecting position by inserting each plate in the slot of the other, as indicated in Figs. 6 and 7. The lower ends of the partitions are attached to the base 3 by means of angular lugs 20 on said partitions, and screws 21 passing through the lugs into the base.

The plate 15 may be secured to the upper ends of the partitions by forming extensions 22 on the upper ends of the two plates 35 constituting said partitions, and making slots 23 in the plate 15 through which the extensions may extend. After passing the plate 15 onto said extensions until it rests on the upper edges of the partitions, the 40 ends of the extensions 22 are bent out of register with the slots 23 so as to prevent upward displacement of the plate 15.

At the side of each bobbin at which the tendency to ballooning is most marked, we 45 provide a restraining means herein shown as a flange 24 extending from the outer edge of the partition and at a right angle to the latter. Said flange extends, in this instance, from the lower end of the partition to the 50 upper end thereof, being bent at its upper end to lie underneath the plate 15. The edge of the flange extends to the end of the straight guide edge 16, thereby serving to limit the reciprocation of the thread along 55 the edge of the plate 15 as the thread unwinds from the bobbin.

The bobbins are connected in series so as to unwind in succession. The lower end a' of the yarn on the bobbin a is connected to 60 the upper end b' of the yarn on the bobbin b ; the lower end b^2 of the yarn on the bobbin b is connected to the upper end c' of the yarn on the bobbin c ; and the lower end c^2 of the yarn on the bobbin c is attached to 65 the upper end d' on the bobbin d . When

bobbin a has been unwound the thread passes across the flange 24 and the guide edge 17 to the upper end of bobbin b , and so on, the empty bobbins being replaced at intervals with full bobbins which are tied 70 in, as hereinbefore described, so as to permit of uninterrupted winding.

When replacing a bobbin, the operator turns the cluster so as to bring said bobbin into a position where it is conveniently accessible, swings the spindle outwardly, pulls off the empty bobbin, puts on a full bobbin, releases the spindle to the action of the spring 11, ties the upper end of the yarn to the lower end on the preceding bobbin (having reference to the order of unwinding), and turns the cluster into the position shown in Fig. 2.

By arranging the spindles in parallel relation a great saving in space is obtained. 85 Such an arrangement of the spindles is made possible by providing the intermediate guides 16. The compact disposition herein shown of the bobbins is rendered practicable by providing the partitions 18.

It will be understood that the invention is not limited to the precise details herein set forth, for various modifications will occur to those skilled in the art.

We claim as our invention:

1. In a bobbin cluster, in combination, a base; a plurality of bobbin spindles mounted thereon in parallel relation, said spindles being adapted to support bobbins connected in series so as to unwind in succession; a common yarn guide; a transverse plate located between the spindles and said yarn guide, said plate having a straight guide edge for each spindle, said edge lying in a vertical plane passing through the axis of the spindle, said plane extending at right angles to a vertical plane passing through the spindle and the said common yarn guide, said plate also having curved edges joining said straight guide edges, the curved edges permitting the yarn to pass freely around the cluster from one bobbin to the other.

2. In a bobbin cluster, in combination, a base; a plurality of bobbin spindles on said base; partitions between the spindles; yarn guide means at the upper ends of said partitions; and a yarn-guiding flange on the outer edge of each partition extending to said yarn-guide means.

3. In a bobbin cluster, in combination, a base; a plurality of bobbin spindles on said base; partitions between the spindles; a transverse plate at the upper ends of said partitions, said plate having guide-edges for the yarn running from the bobbins; and a yarn guiding flange on the outer edge of each partition extending to the edges of said plate.

4. In a bobbin cluster, in combination, a base; a plurality of bobbin spindles on said base; partitions between the spindles; a

common yarn guide; a transverse plate at the upper ends of the partitions, said plate having a straight guide edge for each spindle, said edge lying in a plane passing 5 through the axis of the spindle, said plane extending at right angles to a vertical plane passing through the spindle and the common guide, said straight guide edges being joined by curved edges; and a flange on the 10 outer edge of each partition extending to the adjacent curved edges, one edge of said flange extending to the end of the adjacent straight guide-edge.

5. In a bobbin cluster, in combination, a 15 base; a plurality of bobbin spindles on said base; partitions between the spindles; a common yarn-guide; and intermediate guide means attached to said partitions.

6. In a bobbin cluster, in combination, a 20 base; a plurality of bobbin spindles on said base; partitions between the spindles; a common yarn-guide; and a transverse plate attached to the upper ends of the partitions, said plate having guide edges for the yarn 25 running from the bobbins to the common guide.

7. In a bobbin cluster, in combination, a 30 base; a plurality of bobbin spindles on said base; partitions between the spindles; a common yarn-guide; a transverse plate attached to the upper ends of the partitions, said plate having guide-edges for the yarn running from the bobbins to the common guide; and flanges on said partitions extending to said plate.

8. In a bobbin cluster, in combination, a base; a plurality of bobbin spindles on said

base; sheet-metal partitions between the spindles; a common yarn-guide; said partitions having extensions on their upper ends; 40 and a plate forming intermediate guide means for the yarn, said plate having slots therein receiving said extensions, the latter being bent out of register with the slots to lock the plate in place.

45 9. In a bobbin cluster, in combination, a base; a pair of bobbin spindles at opposite sides of the base, said spindles being provided with pivot means; stop means on said base; and a coiled spring secured at its 50 ends to said spindles and tending to hold them against said stop means.

10. In a bobbin cluster, in combination, a base; a pair of lugs and a stop portion on said base; a bobbin spindle having a transverse pivot pin, the ends of said pin lying in recesses in said lugs; and a spring attached to said spindle between the stop portion and the lugs, for holding said pin 55 in said recesses and said spindle against 60 said stop portion.

11. In a bobbin cluster, in combination, a base; a supporting member having an opening therein, said base being rabbeted to provide a shoulder to rest on the edges of 65 said opening; and a screw seated in said base and having a head adapted to underlie said supporting member and adapted to be turned to clear said member.
